UNITED STATES PATENT OFFICE

2,002,625

RETURNABLE SHIPPING CONTAINER

Robert C. Bender, Davenport, Iowa

Application September 29, 1934, Serial No. 746,069

2 Claims. (Cl. 217—72)

My invention has reference to a returnable shipping container, and has to do more specially with certain improvements on an apparatus of that kind for which Letters Patent of the United States were issued to myself August 14, 1934, numbered 1,970,413. The general features of the device set forth in said former patent have been retained in the present invention, including a spaced ice receptacle and container therein for commodities, and the special advantages relating thereto. The chief purpose of the present invention is to increase the efficiency and simplicity of the former device, and make structural changes therein which will add to the life of the apparatus, and adapt the same more fittingly to use with outer containers of various types and sizes.

The general purposes and facilities which are set out in the former patent are retained in the present invention, such as the use of inner and outer receptacles, with an icing space between; the anchorage of the inner container to the bottom of the outer container, and the suspension of the upper part of the inner container so as to permit a limited amount of lateral adjustment thereof, to relieve any strain that may be placed thereon. The commodity in the inner container and ice on the outside thereof are also separated at all times, and the commodity refrigerated from top to bottom of said container. Drainage facilities are also provided, and reference had to the possibilities of use of the inner container not only with fish barrels which are specially designed for use therewith, but with flour barrels, sugar barrels, and other barrels which were designed for other uses, but can be readily adapted to the purposes set forth herein.

One of the features of the present invention consists in the provision of an inner container the body portion of which is formed of canvas or similar flexible material, which is removably connected with a metal bottom at its lower end and with suspension devices at its upper end. By this means, upon the body portion becoming worn it can be discarded, and replaced by another similar container or bag. By this replacement arrangement the life of the apparatus can be greatly prolonged.

In another modification of the original device which is set forth herein, the inner container is shown formed of metal throughout, of cylindrical form, with a bottom attached to its lower end and a lid for its upper end which are of similar conformation, and which can be used interchangeably by supplying the part to be used at

the bottom with supporting feet and openings for central attachment and drainage. Both of the forms above mentioned have a central attachment with the bottom of the outer container, of a detachable character, so that they can be quickly removed therefrom or replaced, when desired.

Other structural changes will be found in both of the forms mentioned, which have to do with the anchorage of the inner container at the bottom, and the manner of securing the same at the top.

The above named, and other features and advantages of the invention, tending to an increased efficiency and simplicity, and ease of operation thereof, will be more particularly pointed out in the following specification, reference being had to the accompanying drawings, in which:—

Fig. 1 is a vertical medial section of an apparatus which embodies the invention. 20

Fig. 2 is a cross-section on the broken line 2—2 of Fig. 1.

Fig. 3 is a cross-section on the line 3—3 of Fig. 1. 25

Fig. 4 is a cross-section on the same line, with the flexible top of the inner container in another position from that of Fig. 3.

Fig. 5 is a detail of one of the fastenings shown in the foregoing figures. 30

Fig. 6 is a vertical section of another form of the invention on the broken line 6—6 of Fig. 7.

Fig. 7 is a complete cross-section on the line 7—7 of Fig. 6.

Fig. 8 is a detail of the bottom 1, in plan view. 35

Fig. 9 is a side view thereof.

Fig. 10 shows the ring 15, detached, and without the chains 18.

Fig. 11 is a cross-section on the line 11—11 of Fig. 10. 40

As mentioned in said former patent, the invention has to do chiefly with the transportation of fish and other perishable property requiring refrigeration in transit, as by an ice pack, and occasional renewal of the refrigerant on longer hauls.

Referring first to the first sheet of the drawings, the reference number 1 indicates an outer container or barrel, provided with hoops 2, and a bottom 3, containing small perforations 4 for the escape of water and other liquids from the container. Within said container is a container for fish or other commodity, consisting of a cylindrical body portion 5, formed of heavy canvas or similar flexible material, the lower end of 45

which is open, and fits snugly around the flange of a dish-shaped bottom 6, and provided with small openings 6^a for the escape of slime or other liquid matter from the inner container. Secured 5 to the bag 5, near its lower end, are straps 7 of fabric, provided at their inner ends with loops 8, engaged with a harness square 9, surrounding a lock-nut 10 between the bottom 6 and bottom 3 of the outer container, and having a central 10 opening through which passes a bolt 11. Said bolt also passes through openings in the bottom 6 and bottom 3, and is provided at its lower end with a nut 13. The nut 10 also acts as a spacer between the two bottoms, as well as serving to 15 hold the bolt from rotating while the nut 13 is being turned thereon. Washers 12 are interposed between the head of the bolt 11 and the bottom 6, one or more of which washers may be removed to adjust the length of the bolt to greater thicknesses of the bottom of the outer container. The bottom 6 is also provided with feet 14, the lower 20 ends of which are on a plane with the lower face of the spacer nut 10, and assist in keeping the walls of the inner container properly spaced 25 from those of the outer container.

At the upper end of the container 5, on the inside thereof, is a ring 15, held in place by a plurality of small rings 16 in openings 17 in the wall of the container 5. (Fig. 5.) Said rings 16 form the end links of chains 18, which pass outwardly through openings 19 in the sides of the container 5, and are secured in place by pins 20 on the ends of said chains inserted in links in said chains, similarly to the showing in said former patent. The upper ends of the container 5 can thereby be properly positioned to provide a uniform amount of space between the same and the outer container.

The space between the two containers is filled 40 with cracked ice, which also finds its way between the bottoms thereof, tending to the preservation of the contents of the container 5 entirely to the bottom thereof.

The body portion of the container 5 is extended 45 upwardly beyond the ring 15, and is adapted to be folded downwardly into a pair of flaps 23, fastened by a lacing 24, one end of which is secured to a link 25 fixed to one of said flaps. Other flaps 28 are foldable transversely of the flaps 23, 50 and are connected by a lacing 27, hitched to a link 28 on one of said flaps. The upper end of the container is thus closed so that some of the ice can be filled in above the container with no danger of getting into same. When the ice has 55 been filled in to the top of the outer container such top is closed by a suitable cover 29, held in place by the upper hoop 2, which is removable for that purpose.

The container is also shown provided with 60 links 30, in the form of harness-D's, attached thereto by straps 31 just below the ring 15. The chains 18 pass through said links, thereby assisting in supporting the container 5 and its load, and preventing the chains 18 from wearing or tearing the upper ends of the openings 17. The fabric surrounding said openings can also be reinforced by other pieces of fabric attached thereto.

If it is desired to remove the inner container 70 this can be quickly done by removing the nut 13, and disconnecting the chains 18 from the outer container. It can be as quickly returned to its position. If it is desired to renew the body portion of the container 5 the container is removed 75 as before mentioned, the ring 15 removed from

the upper end of said container by passing the chains 18 through the openings 17, and the bottom 6 lifted from the lower end of the body portion. A new fabric body is then provided and the bottom 6 and ring 15 re-installed therein. This form of container is also collapsible upon being removed from the former container, and occupies a less amount of space in that condition. 5

On account of various kinds of barrels being made use of for the outer container it is usually 10 necessary to provide such barrels with openings 19 for the passage of the chains 18. Said chains are of sufficient length to conform readily to the requirements of adjustment to provide a suitable and uniform spacing between the inner 15 and outer containers.

In Figs. 6 and 7 of the drawings there is set out another form of the invention, wherein the number 32 indicates the outer container, fitted with a bottom 33, and closed at the top by a 20 cover 34. Centrally of said container is a commodity container 35, formed entirely of metal, and rigidly connected with a bottom 36 at the lower end of the body portion, by means of rivets or similar means. The bottom 36 is identical in 25 shape and size with the bottom 6 of the other form, and said bottoms can be used interchangeably with either form. The bottom 33 is secured to the bottom 36 by means of a bolt 37, passing through openings in said parts and in a lock-nut 38, which bolt is held in place by a nut 39, anchoring the container in place. The bottom 36 is also provided with feet 40 as in the other form, and with openings for drainage. The container 35 is also fitted with a cover 41, similar in shape and size with the bottom 36, and capable of being substituted therefor, except that when used as the bottom part it must be fitted with the feet and drainage openings. It will be observed that the bottom member 36 is 40 duplicated not only in the cover 41, but also in the bottom 6, so that any of said parts can be used interchangeably, by slight adaptations.

The container 35 is also provided with a ring 42 on the outside thereof, adjacent to the lower 45 edge of the cover, and secured to the container by eye-bolts, with which are connected chains 43, passing through openings 44 in the container 32, and secured in place by pins on the ends of said chains. Connected with the chains 43 are chains 45, extending above the cover 41, and attached to a ring 46 at a central point, holding said cover from accidental release. This part of the device is provided with a further sealing effect by forming a loop 47 in one of the chains 45 and engaging said loop with one of the chains 43. The end of the loop is fitted with a pin 48, for securing the loop in place. When it is desired to remove the cover 41 the loop 47 is disconnected from the chain, and the chains 45 and ring 46 60 moved to one side, without disconnecting any other of the chains.

The ring 42 is preferably formed with a flat face against the container, as in Fig. 6, but the ring 15 is preferably formed with a flat face 65 against the inner face of the container, as in Figs. 1 and 11, with a convex inner face, which will have a minimum amount of interference with products being placed in the container or removed therefrom. 70

What I claim, and desire to secure by Letters Patent, is:—

1. A shipping package for the purpose named, comprising an outer container, an inner container having a fabric body portion, a dish- 75

shaped metal bottom connected detachably with the lower part of the body portion, a ring member connected removably with the upper part of said body portion, means connecting said ring member with the outer container, and means connecting the bottom of the inner container with the bottom of the outer container.

2. A shipping package, comprising an outer container, provided at its lower part with drainage facilities, an inner container having a fabric body portion provided at its upper end with a series of openings, chains passing through said openings, a ring within said body portion con-

nected with said chains, means for connecting said chains with the outer container, releasably, so as to permit the removal of said chains and ring from said body portion, auxiliary supports fixed to said body portion and connected with said chains, connecting straps at the lower end of said body portion, a dish-shaped bottom held removably by said straps, provided with openings for drainage, and means for connecting said bottom detachably with the bottom of the outer container.

ROBERT C. BENDER.
